CENTRIFUGAL PUMP

Harry J. Sadler, St. Paul, and Ramon Pareja, Minneapolis, Minn., assignors to Hypro, Inc., St. Paul, Minn.

Filed Jan. 9, 1970, Ser. No. 20,859

Term of patent 14 years

Int. Cl. D15—02

U.S. Cl. D65—1

FIG. 1 is a perspective view taken from one side of a centrifugal pump embodying our new design;

FIG. 2 is an elevational view taken from the side opposite that shown in FIG. 1;

FIG. 3 is a front elevational view thereof;

FIG. 4 is a rear elevational view thereof; and

FIGS. 5 and 6 are top and bottom plan views thereof, respectively.

We claim:

The ornamental design for a centrifugal pump, substantially as shown.
